ATTORNEY

UNITED STATES PATENT OFFICE.

PETER G. MACGREGOR, OF NEW YORK, N. Y., ASSIGNOR TO PYRENE MANUFACTURING COMPANY, A CORPORATION OF DELAWARE.

PUMP.

Application filed April 15, 1919. Serial No. 290,261.

To all whom it may concern:

Be it known that PETER G. MACGREGOR, a citizen of the United States, and resident of the city, county, and State of New York, has invented certain new and useful Improvements in Pumps, of which the following is a specification.

This invention relates generally to pumps, more particularly to pumps of the portable 10 hand-operated type adapted for use in throwing a stream of liquid through a suitable nozzle from a receptacle.

The invention has for an object to provide a novel arrangement of parts in a pump 15 of this type whereby the discharge of the liquid is maintained by air pressure during the periods when the pump piston momentarily comes to rest at the end of each stroke, thus providing a continuous flow of the liquid 20 uid from the nozzle.

A further object is to provide a construction in which the passage through the pump presents no restricted portions, thus increasing the ease and smoothness of operation of 25 the pump.

For further comprehension of the invention and of the objects and advantages thereof, reference will be had to the following description and accompanying drawings, 30 and to the appended claims in which the various novel features of the invention are more particularly set forth.

Fig. 1 of the drawings is a sectional view of a pump embodying the invention.

35 Fig. 2 is a fragmentary sectional view of a portion of the handle, taken at a right angle to Fig. 1.

Fig. 3 is an enlarged horizontal section on the line 3—3 of Fig. 1.

40 In the drawings, the body of the pump cylinder is shown at 1 and may be conveniently made from metal tubing. The upper end of this tubing is threaded into the neck 2 of a globular head 3, which is preferably 45 of larger diameter than the tubing, the neck 2 being formed with an integral surround-

ing flange 4 by which the pump may be secured in place in a suitable receptacle, a portion of which is shown at 5. As here shown,

50 a ring 6 is secured to the inner side of the receptacle wall 5, bolts 7 passing through suitable openings in this ring and in the wall of the receptacle and flange 4. The liquid is discharged through the head 3 and the latter 55 is formed with a tubular projection 8 to

which the end of a length of hose 9 may be attached and which is provided with a nozzle 10, of the usual construction.

The piston of the pump, to be later referred to, is operated by a hollow piston rod 60 11 which extends through a suitable opening in the globular head 3, a stuffing box, indicated generally at 12, being provided to prevent leakage.

The upper end of the piston rod is threaded 65 into the bottom of a handle 13, the handle being provided in its lower portion with an enclosed chamber 14 (Figs. 1 and 2) into which the hollow piston rod 11 leads, the piston rod being open at both ends and extending completely through the piston at its 70 lower end.

A peripheral indentation or corrugation 15 is formed near the lower end of the piston rod 11 and a ring 16 is soldered or otherwise secured in this indentation about the exterior of the piston rod 11, the indentation 15 providing a seat for a one-way valve 17 75 slidably mounted in the piston rod 11 and the ring 16 providing an abutment shoulder 80 for the piston.

The piston comprises a flanged sleeve 18 which is slipped over the lower end of the piston rod 11 with its flange engaging the ring 16, this sleeve being surrounded by a 85 piston ring 19 of suitable material held in place by a nut 20 threaded on the lower end of the piston rod 11.

The valve 17 is in the form of a cup whose closed end seats on the shoulder provided 90 by the indentation 15 when in its lower position and which has a sliding fit in the piston rod 11, movement of the valve away from its seat 15 being limited by a pin 21 extending across the piston rod 11. A series 95 of ports or openings 22 are provided in the wall of the piston rod 11 just above the indentation 15, while a second series of ports or openings 23 are provided in the said wall at a point above the upper limit of movement of the valve 17.

The lower end of the pump cylinder 1 has attached thereto a head 24, which is recessed in its lower portion, as at 25, and is provided with a central aperture 26 in its 105 upper portion, this aperture being closed by a valve 27 having a cylindrical extension 28 on one side which slides in the aperture 26 and constitutes a valve stem, this extension being formed with a series of ports or open- 110

ings 29 located close to the upper closed end of the valve 27.

The valve 27 seats on the top of the head 24 and movement thereof away from its seat is limited by a pin 30 extending across the piston cylinder 1. The lower end of the head 24 may be covered with a perforated disk 31.

The cross sectional area of the piston rod 11 is approximately one-half that of the cylinder 1 so that the active piston area is substantially the same as the opening provided through the piston by the piston rod 11. The opening 26 through the head 24 is also of the same area and, as a consequence, the intake to the pump cylinder is at all points of substantially as large an area as the active piston area and no extra pressure is required to draw or force the liquid 20 through in its flow to the active cylinder space, and the pump may be operated with a minimum of effort for a given nozzle pressure. It will, of course, be understood that the passage provided by the openings 22 and 25 29 and by the perforated cap 31 are of equal area to that through the piston rod.

The manner in which the pump operates is as follows: The upstroke of the piston draws the liquid in through the opening 26 in the head 24, the valve 27 lifting from its seat and permitting the liquid to flow through the ports 29 in the cylindrical valve stem 28 to the pump cylinder 1 below the piston. At the same time the piston discharges the liquid which the previous down stroke has fed into the cylinder above the piston.

When the piston starts its downstroke the valve 27 closes and the valve 17 moves upwardly to the stop 21, uncovering the ports 22 in the piston rod 11 and the liquid in the pump cylinder 1 below the piston passes through the open lower end of the piston rod and through these ports 22 into the active cylinder space in the pump cylinder 1 above the piston.

Since the interior of the hollow piston rod above the valve 17 is at all times in communication with the cylinder space above the piston through the opening 23 it follows that the pressure exerted in both up and downstrokes will tend to back the liquid up in the piston rod 11 against the cushion of air which will be formed in the closed space formed by the piston rod 11 and the chamber 14 in the handle 13, thus creating an air pressure on the liquid substantially equal to the piston pressure.

When the piston pressure or movement 60 momentarily ceases at the end of each stroke this air pressure forces the liquid which has been backed up in the rod 11 downward and thus continues the discharging action until the piston again becomes active, causing a continuous stream to be discharged

from the nozzle by the reciprocation of the piston. It will be understood, of course, that a very slight diminution in the flow through the nozzle during the movement of the piston results from the backing up of 70 the liquid in the hollow piston rod. The amount of liquid entering the rod is comparatively small, by reason of the relatively light pressure exerted on the handle 13, the chamber 14 being formed in the handle to 75 provide the proper volume of air necessary for sufficient compression to insure of sufficient liquid entering the piston rod to continue the stream from the nozzle during the momentary intervals between the strokes. 80

The air pressure in the piston rod does not affect the action of the valve 17 except to tend to cause it to close more quickly on the termination of the downstroke and to open more slowly at the commencement of the 85 downstroke in the event of a retarded application of full pressure on the piston at the commencement of each stroke. This, however, does not affect the continuity of the discharge, the transfer from the air 90 cushion to the piston as the active discharging medium being instantaneous once the piston pressure overbalances the stored air pressure. In actual operation, there will be a slight rising and falling of the liquid 95 in the piston rod 11 at each stroke of the piston.

The globular head 3 serves as a reservoir to ensure against the occurrence of any slight fluctuations in the stream. It will 100 be understood, of course, that a stroke or so will be required to fill the pump at the start before it operates continuously as just described.

The particular piston construction and 105 arrangement herein set forth provides, in a direct hand operated pump with its resultant restricted area, a maximum passage for the liquid through the piston.

What I claim is:—

1. In a device of the class described, a piston rod in the form of a tube having a peripheral indentation in the wall thereof near its lower end, a piston element mounted on and surrounding said piston rod below 115 said indentation, and a valve slidably mounted in said piston rod and adapted to seat upon said indentation to control the passage through said piston.

2. In a device of the class described, a piston rod in the form of a tube having a peripheral indentation in the wall thereof near its open lower end, a ring secured in said indentation, a piston element surrounding the lower end of the piston rod and held against longitudinal movement by the said ring, and a valve slidably in the said piston rod and adapted to seat upon the said indentation to control the passage through the piston.

3. In a device of the class described, a piston rod in the form of a tube having a peripheral indentation in the wall thereof near its lower end, a ring secured in said indentation, a piston mounted on the lower end of said rod and held against longitudinal displacement by said ring, an opening in the wall of said rod above the said indentation, and a valve slidable in the said rod and adapted to seat upon the said indentation to close the said opening, said valve comprising a cup having a slidable fit in the said rod.
4. In a device of the class described, a hollow piston rod in the form of a tube having a peripheral indentation in the wall thereof near its lower end, a ring secured in said indentation, a sleeve upon said rod having a flange adapted to bear on the said ring, a piston element surrounding the said sleeve, and a nut threaded upon the lower end of the piston rod and holding said piston element upon the said sleeve.

Signed at the city, county and State of New York, this 11th day of April, 1919.

PETER G. MACGREGOR.
